UNITED STATES PATENT OFFICE.

HENRY H. CUMMINGS, OF BOSTON, MASSACHUSETTS; IRVING C. DECATUR AND ESTHER CUMMINGS EXECUTORS OF SAID HENRY H. CUMMINGS, DECEASED.

LACING.

Application filed May 15, 1922. Serial No. 560,936.

To all whom it may concern:

Be it known that I, HENRY H. CUMMINGS, a citizen of the United States, and resident of Boston, in the county of Suffolk and State 5 of Massachusetts, have invented an Improvement in a Lacing, of which the following description, in connection with the accompanying drawings, is a specification, like letters on the drawings representing like parts.

10 My present invention is an improved and novel form of lacing and lacing tip employing a metallic tip which can be readily, firmly and easily applied to either tubular or flat lacings.

15 In my prior application, Ser. No. 462,019, filed April 16, 1921, I have illustrated a novel form of lacing tip wherein a metallic tip member was employed which was adapted to be fitted within a lace, and to have a 20 portion of the metallic tip encircling about the outside of the lacing, as well, also, as forming a metallic point, and presenting a lacing tip with the metal both inside and outside and so applied as to be firmly interlocked with the fabric of the lace.

25 My present invention is an improvement in this type of metallic tip and lacing, but enables the same to be fitted much more simply, quickly and more economically than 30 formerly, and to give a flush metallic pointed lacing tip, which is so firmly interlocked as to be free of all danger of pulling off or becoming dislodged.

35 Further features, novel combinations of parts and advantages will be hereinafter more fully pointed out and claimed.

Referring to the drawings, illustrating a preferred embodiment of the invention,

40 Fig. 1 is a side view of one form of my improved blank, shown on an enlarged scale;

Fig. 2 is an end view of the blank of Fig. 1, illustrating the preferable concavo-convex form;

Fig. 3 being an opposite end view;

45 Fig. 4 is a view illustrating the metallic blank applied to a tubular lace;

Fig. 5 being a side view of the same;

Fig. 6 illustrates the preliminary bending action in incorporating the metal tip of the 50 lace;

Fig. 7 is a showing of the next step; and

Fig. 8 illustrates the completely tipped and pointed lace;

Fig. 9 illustrates the application of the tip 55 to a flat or ribbon lace; and

Fig. 10 is an end view of the tipped lace without the metallic pointing feature.

Referring to the drawings, my improved blank comprises a shank or body member 1, having a plurality of saw teeth 2, 2, formed substantially as shown to lock and interlock with the lacing. The shank 1 is attached to a head 5 by a pair of neck members 4, 4, leaving a recess 6. The head 5 has a pair of wing-like projections 7, 7, preferably extending beyond the line of the teeth 2 or the shank 1. While the shank 1 is preferably given a concave shape in one direction,—to facilitate the rolling and interlocking of the lace and blank, the head 5 is given a corresponding concavity in a reverse direction, or at least the wings 7 are bent, as clearly shown in Figs. 2 and 3.

The tip as thus far described is of suitable form to apply to and tip a flat lacing, and the lace thus tipped is illustrated at Fig. 10, and will be further described. However, I prefer to form on the head 5 a portion 10 which may be stamped out with the formation of the neck portions 4, 4, and space 6. 80 This piece 10 will afford a metallic means to give a metal point to the lace and may be used or not as desired, according to whether or not a metallic tip or point is desired. With the blank formed and slightly concaved as illustrated in Figs. 1, 2 and 3, I then apply the same to a lace, Figs. 4, 5, 6 and 7, illustrating the same as applied to a tubular lace 12, having the blank within the open end of the tubular lace, as illustrated in dotted lines 90 Figs. 4 and 5. Thereupon the head 5 and wings 7 are turned or clamped backwardly, as illustrated in Fig. 6, thus allowing the reverse contour of the head 5 to fit in with the same convexity and contour of the shank 1; the two portions, shank 1 and head 5, being originally convexed in opposite directions in order to be thus convexed in similar directions when the head 5 is doubled over, the reduced neck portions 4, 4, readily permitting this action and in case the metallic tip 10 is utilized the latter will be thus brought upwardly and outwardly as shown in Fig. 6. The recess 6 between the necks 4, 4, permits a firm interlocking of the lace ends, as well as engagement of the saw teeth 2. Thereupon the end pointing piece 10 is bent over, as shown in Fig. 7, and thereafter the entire shank, wings 7 and lace are subjected to a clamping action which rolls and 100

105 Fig. 8 illustrates the completely tipped and pointed lace;

110 Fig. 9 illustrates the application of the tip to a flat or ribbon lace; and

interlocks the same firmly and securely around the lacing, as illustrated in Fig. 8, giving a completely encircled metallic tip with metal point as clearly shown in Fig. 8. 5 The reduced neck portions 4 allow the encircling head 5 and wings 7 to fit snugly and flush with the rest of the lacing, so that the completely tipped metal part is flush with the rest of the lace in a manner similar to 10 the construction shown in my said prior application.

A duplicate arrangement is possible with a flat or ribbon lace, illustrated in Figs. 9 and 10. In this form the ribbon lace 15 receives 15 the shank, the head 5 is bent over, the member 10 clamped in position and then the entire lace rolled or forced into rotund and interlocking engagement. Fig. 10 illustrates the tip applied to either a tubular or flat lace 20 without the tongue or point member 10, the tipping action being identical except for omitting the folding over of the member 10.

It will thus be seen that I have devised a novel form of lace and tip blank therefor, 25 which can be stamped out at a single operation, readily concaved as a preliminary forming and tipping action, applied to a flat or ribbon lace, and firmly and immovably interlocked therewith by a simple process and 30 by any suitable clamp or machine, as well as by hand.

The metal blank may be of extremely thin

material, preferably of non-corrosive substance, such as brass, zinc or other alloy. The lacing is not only pointed but is protected and the flush position of the encircling metal portion eliminates any danger of projecting points, ridges or the like to be caught and pulled off. 35

My invention is further described and defined in the form of claims as follows: 40

1. A lacing, having a metallic stiffener for the tip end, said stiffener comprising a shank portion having a reduced neck formed with a central recess, said neck being interlocked with and covered by an end part of the lacing, said stiffener including a cooperating metallic tip portion bent over one end of the lacing, and interlocked with both lacing and metal. 45

2. A metallic blank for tipping shoe laces or the like, comprising a shank portion, a neck portion having an opening therein, and a head, the shank being adapted to be interlocked with the lacing and the head being 50 constructed for encircling the lace at the shank portion, said shank, neck and head portions being so proportioned as to enable the encircling metal of the head to lie flush with the encircling lacing on the shank. 55

In testimony whereof, I have signed my name to this specification. 60

HENRY H. CUMMINGS.
